UNITED STATES PATENT OFFICE.

THEODOR GARDIN, OF ESSEN-ON-THE-RUHR, GERMANY, ASSIGNOR TO
FRIED. KRUPP, OF ESSEN-ON-THE-RUHR, GERMANY.

CONNECTION FOR THE MEETING ENDS OF RAILS.

SPECIFICATION forming part of Letters Patent No. 741,482, dated October 13, 1903.

Application filed May 13, 1903. Serial No. 156,977. (No model.)

To all whom it may concern:

Be it known that I, THEODOR GARDIN, a subject of the Emperor of Germany, and a resident of 76 Kaiserstrasse, Essen-on-the-Ruhr, 5 Germany, have invented certain new and useful Improvements in Connections for the Meeting Ends of Rails, of which the following is a specification.

This invention relates to those connections for the meeting ends of rails in which downwardly-projecting hangers from the fish-plates have transverse under tongues beneath the joint in order to insure an equal depression of the meeting rail ends under the load imposed by passing wheels. The invention aims to produce a more effective joint of this type in the direction of insuring uniformity of depression in the meeting rail ends with the fish-plates, as well as preventing the separation of the fish-plate ends from the foot of the rail and preventing the development of the so-called "hammering" at the joints. At the same time a weakening of the fish-plates in available cross-section is avoided. These objects are essentially attained according to the present invention by having the meeting ends supported by a longitudinal under yoke, which in turn rests upon cross-tongues which are introduced 30 through the fish-plate hangers near their ends.

In the accompanying drawings one embodiment of the rail-joint forming the subject of the present invention is illustrated by 35 way of example.

Figure 1 is a side elevation of the joint; Fig. 2, a section on the line 2 2, Fig. 1; and Fig. 3, a section on the line 3 3, Fig. 2. Fig. 4 is a view similar to Fig. 2, showing spring-lamellæ instead of a solid yoke. Fig. 5 is a section on the line 5 5, Fig. 4.

The abutting ends of the rails A are connected by the angular fish-plates B in the usual manner. The under hangers b' of the fish-plates are provided near their ends with recesses b², through which cross-tongues C in the form of double wedges are introduced. Upon these cross-tongues and between the under hangers b' rests a longitudinal yoke D,

the intermediate elevated portion of which 50 supports the meeting ends of the rails. By driving in the wedges C the yoke D will be firmly pressed against the bases of the rails.

When a loaded wheel reaches the end of a rail upon which it is running, the latter bears 55 approximately upon the middle of the yoke D, which transfers half of the load to each of the cross-tongues C at the ends of the fish-plate hangers. In consequence of the simultaneous and equal loading of the two 60 cross-tongues C it will be seen that the fish-plates, and through them the two rail ends, will be depressed equally. Hence, on the one hand, a lifting of the fish-plate ends and, on the other hand, all relative vertical movement of the meeting ends will be prevented, and a smooth and practically shockless passage of the wheel to the rail end onto which it runs will always take place.

Obviously in the new construction the action on the fish-plates is essentially more favorable than in those joints in which a cross-tongue bears immediately beneath the joint of the rails, besides which a weakening of the fish-plates in available cross-section is 75 prevented.

Instead of making the longitudinal yoke D of a rigid piece it could be made of superposed spring-lamellæ D (see Figs. 4 and 8) 80 in order to render the joint elastic.

Having thus described the invention, the following is what is claimed as new therein:

1. A rail-joint having fish-plates, a longitudinal yoke supporting the meeting ends of the rails, and transverse wedges supported 85 by the fish-plates and in turn supporting the longitudinal yoke.

2. A rail-joint having fish-plates, transverse tongues in the form of adjustable wedges, supported in the ends of said fish-plates, and a longitudinal yoke resting upon 90 said tongues and in turn supporting the meeting ends of the rails.

3. A rail-joint having a longitudinal supporting yoke upon intermediate points of 95 which the meeting ends of the rails bear; said yoke being constructed of spring-lamellæ and supported at its ends.

4. A rail-joint having a longitudinal supporting -yoke upon intermediate points of which the meeting ends of the rails bear; said yoke being constructed of spring-lamellæ and supported at its ends, by transverse tongues, which are in turn supported in under hangers from fish-plates.

The foregoing specification signed at Dusseldorf this 1st day of May, 1903.

THEODOR GARDIN.

In presence of—

PETER LIEDER,

WILLIAM ESSENWEIN.
